W. M. SCOTT

SWITCH HOUSING STRUCTURE

Filed Feb. 4, 1922

INVENTOR
William M. Scott
BY
Cornelius L. Scott
his ATTORNEY.

UNITED STATES PATENT OFFICE.

WILLIAM M. SCOTT, OF TREDYFFRIN TOWNSHIP, CHESTER COUNTY, PENNSYLVANIA.

SWITCH-HOUSING STRUCTURE.

Application filed February 4, 1922. Serial No. 534,024.

To all whom it may concern:

Be it known that I, WILLIAM M. SCOTT, a citizen of the United States, residing in Tredyffrin Township, in the county of Chester, State of Pennsylvania, have invented a new and useful Switch-Housing Structure, of which the following is a specification.

My invention relates to structure for mounting and housing electric switches, 10 automatic circuit breakers, and the like.

In accordance with my invention, there is provided a supporting or conductor housing to which are hinged, independently of each other, a base for carrying the switching or automatic circuit breaker mechanism, 15 and a second housing enclosing the switching or circuit breaker mechanism.

Further in accordance with my invention, 20 a plurality of switching units or mechanisms, as a plurality of double arm automatic circuit breakers, is mounted upon a common base within a common housing, and the manual actuating and tripping members for the several circuit breaker mechanisms 25 are carried by a common wall, which may swing toward and away from operative relation to all of the switch or circuit breaker mechanisms.

My invention resides in the features of 30 construction and combination hereinafter described and claimed.

For an illustration of some of the various forms my invention may take, reference is to be had to the accompanying drawings, in 35 which:

Fig. 1 is a side elevational view of apparatus embodying my invention.

Fig. 2 is a top plan view of the same.

Fig. 3 is a front elevational view of the 40 same.

Fig. 4 is an end elevational view with the housings and base swung apart.

Fig. 5 is an end elevational view of a 45 modification, with the housings and base swung apart.

Referring to Figs. 1 to 4 inclusive, A is a housing or box of any suitable material, 50 preferably sheet or cast metal, which, in the example illustrated, serves as a supporting housing or a housing receiving and enclosing the conductors communicating with the switching or circuit breaker mechanism. The housing A may be secured by any suitable means, as screws 1, 1, to any suitable 55 support, as a wall, pillar or the like.

The supply and consumption circuit conductors may be led into and from the housing A through the suitable openings 2, at which usual conduits or conductor housing pipes are connected in well known manner, as for example, as indicated in my prior Letters Patent No. 1,389,996. At any suitable position on the housing A, as for example, at its forward edge, there are provided hinge members 3, secured to the housing A, and supporting any suitable hinge elements, as hinge pins 4.

A base 5, preferably of insulating material, as slate or the like, has secured thereto the hinge members 6 terminating at their upper ends in hinge hooks 7 embracing or hooked upon the aforesaid hinge pins 4 carried by the housing A. The base 5 is therefore hinged to the supporting housing A at its front edge, and forms a closing wall 70 for that housing, or a wall common to or dividing the supporting housing A from the second housing B, having the front wall 8. The housing B has secured thereto the hinge members 9 terminating in eyes or, as indicated, hinge hooks 10, which also co-act or engage with the aforesaid hinge pins 4, whereby the housing B is pivoted to the supporting housing A, but independently of the base 5, whereby that base and the housing B may swing independently of each other upon the housing A. This feature of independent pivoting is well indicated in Fig. 4, where the base 5 and second housing B are 80 shown in different positions with respect to the housing A while hinged thereto at 4.

While the members 7 and 10 are preferably hooks, whereby the base 5 and housing B are detachably hooked or hinged upon the housing A, it will be understood that these hook members may be completely closed circumferentially, and thereby completely embrace the hinge pins 4, upon removal of which, however, the parts may be 95 separated.

Upon the front face of the base 5, as indicated in Figs. 1 and 3, is mounted switching mechanism, automatic circuit breaker mechanism, or the like. In the example illustrated, there is shown a plurality of automatic circuit breaker mechanisms, each of which comprises two breaker or switching arms or mechanisms constituting so-called "double arm" circuit breaker mechanism, such, for example, as illustrated in the afore- 105 110

said Letters Patent No. 1,389,996. Electrical connections are made, as indicated in the aforesaid patent, from the conductors in the conductor housing A to the studs 11, 11, 5 extending into the housing A through the base 5 from the switching mechanism on its front face. Carried by the wall 8 of the second housing B is a rotary or oscillatory operating member 12 disposed within the 10 housing B for successively closing the different arms of each switching or circuit breaker mechanism, and operable from the exterior of the housing by the handle 13; the wall 8 of the housing carries also the plunger 14, 15 whereby the automatic circuit breaker mechanism may be manually tripped, as explained in the aforesaid Letters Patent.

By screws 15, Fig. 3, passing through plate 15^a and threaded into members 16, Fig. 1, 20 secured on the inside of the housing A, the base 5 is held in fixed position with respect to the housing A. The ends 17, Figs. 1 and 3, of the outwardly extending bars 18, Figs. 1 and 3, are threaded into plates 15^a. The 25 bars 18 are rotatably supported by U-shaped members 18^a secured to housing B. The outer ends of bars 18 are provided with screw driver slots 19, access to which slots is prevented by the bars 20 of padlocks passing 30 through the lugs 21 adjacent the heads of the screws 17; this structure being similar to that indicated in the aforesaid Letters Patent. The padlocks keep the housing B locked closed, but upon removal of the padlocks the screws 17 may be removed and then the housing B may be swung outwardly on the pivot pins 4, as indicated in Fig. 4, and unhooked therefrom and removed. Similarly, after the housing B is removed, the 40 screws 15 may be removed and the base 5 may be swung outwardly, as indicated in Fig. 4, and unhooked from the housing A and removed.

As indicated in Fig. 5, the outer wall 8 of the second housing B may be pivoted to that housing, as at 8^a, and may be locked closed by a padlock passing through a spring catch 22, which extends through a slot in the door 8 and has a hole for receiving the bar of the padlock, as described, for example, in my co-pending application Serial No. 496,816.

As will be noted from Figs. 2 and 3, there is disposed within the same second housing B a plurality of switching or circuit breaker mechanisms, in detached relation to which are disposed the aforesaid operating members 12, 13, 14 carried by the common housing wall 8, which, as illustrated in Fig. 5, may be pivoted to the housing B, or, as indicated in Figs. 1, 2 and 3, may be fixed thereto.

While in the examples illustrated the base and second housing are hinged upon horizontal axes, it will be understood that they

may be hinged upon vertical axes, or that one of them may be hinged upon a horizontal axis and the other upon a vertical axis.

What I claim is:

1. The combination with a housing, of a base member carried thereby, fixed and movable contacts of switching mechanism carried by said base member, connecting means extending from said switching mechanism through said base member into said housing, 75 and a second housing enclosing said switching mechanism hinged to said first named housing independently of said base member.

2. The combination with a housing, of a base member hinged thereon, fixed and movable contacts of switching mechanism carried by said base member, connecting means extending from said switching mechanism through said base member into said housing, 80 and a second housing enclosing said switching mechanism and pivoted to said first named housing independently of said base member. 85

3. The combination with a housing, of a base member carried thereby, fixed and movable contacts of switching mechanism carried 90 by said base member, connecting means extending from said switching mechanism through said base member into said housing, a second housing enclosing said switching mechanism hinged to said first named housing independently of said base member, 95 means for securing said base member to said first named housing, and means securing said second housing to said base member. 100

4. The combination with a housing, of a base member hinged thereon, fixed and movable contacts of switching mechanism carried by said base member, connecting means extending from said switching mechanism through said base member into said housing, 105 a second housing enclosing said switching mechanism and pivoted to said first named housing independently of said base member, means for securing said base member to said first named housing, and means securing said second housing to said base member. 110

5. The combination with a housing, of a base member hinged thereon, fixed and movable contacts of switching mechanism carried by said base member, connecting means extending from said switching mechanism through said base member into said housing, 115 and a second housing enclosing said switching mechanism and pivoted to said first named housing co-axially with but independently of said base member. 120

6. The combination with a housing, of a base member carried thereby and forming a wall thereof, fixed and movable contacts of switching mechanism carried by said base member, connecting means extending from said switching mechanism through said base member into said housing, 125 and a second housing enclosing said switching 130

mechanism and pivoted independently of said base member to said first named housing at an edge thereof adjacent said base member.

6 7. The combination with a housing, of a base member hinged thereon at one edge thereof, fixed and movable contacts of switching mechanism carried by said base member, connecting means extending from 10 said switching mechanism through said base member into said housing, and a second housing enclosing said switching mechanism and pivoted at said edge of said first named housing independently of said base member.

15 8. The combination with a supporting housing, of means for securing the same to a support, a second housing pivoted to said first named housing, a base member independently pivoted to said first named housing and forming a wall common to said housings, fixed and movable contacts of switching mechanism on said base within one of said housings, and connecting 20 means extending from said switching mechanism through said base member into the other of said housings.

9. The combination with a base member, of a plurality of automatic circuit breaker units carried by said base, an enclosing housing common to said units, and operating mechanisms for said units carried in detached relation thereto on the same wall of said housing.

35 10. The combination with a base member, of a plurality of automatic circuit breaker units carried by said base, an enclosing housing common to said units, said housing having a pivoted door, and operating 40 mechanisms for said units carried in detached relation thereto on said door.

45 11. The combination with a housing, of a base member pivotally mounted with respect thereto, fixed and movable contacts of switching mechanism carried by said base member, and a second housing enclosing said switching mechanism and pivoted independently of said base to said first named housing.

50 12. The combination with a support, of a switch base pivotally carried thereby, fixed and movable contacts of switching mechanism mounted on said base, and a housing for said mechanism mounted independently of said base upon said support.

55 13. The combination with a support, of a base member, fixed and movable contacts of switching mechanism carried by said base member, a housing for said switching mechanism, and means for pivotally mounting

said base and said housing for independent movement with respect to said support.

14. The combination with a housing, of automatic circuit breaker mechanism comprising co-operating relatively fixed and 65 movable contact structures, restraining means, and automatic tripping mechanism, a base member carrying said automatic circuit breaker mechanism pivoted upon said housing, a second housing independently 70 pivoted upon said housing and enclosing said circuit breaker mechanism, connectors extending through said base member from said circuit breaker mechanism, and conductors extending from the exterior into 75 said first-named housing and detachably connecting with said connectors.

15. The combination with a housing, of automatic circuit breaker mechanism comprising co-operating relatively fixed and 80 movable contact structures, restraining means, and automatic tripping mechanism, a base member carrying said automatic circuit breaker mechanism pivoted upon said housing, a second housing independently pivoted upon said housing and enclosing said circuit breaker mechanism, connectors extending through said base member from said circuit breaker mechanism, conductors extending from the exterior into 85 said first-named housing and detachably connecting with said connectors, and means operable from the exterior of said second housing carried thereby in detached relation to said movable contact structure for 90 resetting said circuit breaker.

16. The combination with a housing, of automatic circuit breaker mechanism comprising co-operating relatively fixed and 100 movable contact structures, restraining means, and automatic tripping mechanism, a base member carrying said automatic circuit breaker mechanism pivoted upon said housing, a second housing independently 105 pivoted upon said housing and enclosing said circuit breaker mechanism, connectors extending through said base member from said circuit breaker mechanism, conductors extending from the exterior into said first-named housing and detachably connecting 110 with said connectors, and said second housing having a movable wall, and means operable from the exterior of said second housing carried by said movable wall in detached relation to said movable contact 115 structure for resetting said circuit breaker.

In testimony whereof, I have hereunto affixed my signature this 3rd day of February, 1922.

WILLIAM M. SCOTT.
